UNITED STATES PATENT OFFICE

ARTHUR E. H. BARILI AND JACOB A. HYLE, OF LOS ANGELES, CALIFORNIA, ASSIGNEES
TO EMPIRE RAILWAY SUPPLY CORPORATION, A CORPORATION OF DELAWARE

RAILWAY-RAIL ANCHOR

Application filed August 26, 1929. Serial No. 388,591.

This invention pertains to new and novel improvements in rail anchors formed from a single piece of metal especially designed to be fixedly secured to the base portion of a railway track rail, and in engagement with stationary parts of the railway road bed for the purpose of preventing longitudinal displacement of the track rails during the travel of the rolling stock thereover, said invention 10 constituting an improvement on the rail anchor set forth in an application filed by us under date of July 3, 1929, bearing Serial No. 375,856.

The prime object of the invention is to provide a simple, novel, durable, economical, practical and efficient rail anchor formed from a single plate or bar of suitable high grade spring steel of the desired dimensions and possessing unusual strength, which may 20 be easily and readily applied to the base of a track rail and securely maintained in its proper operative position thereon, and which will always effectively grip and clamp the rail base and co-operate with a stationary 25 part of the railway road bed to prevent the track rail from creeping.

Another object of the invention is to so construct the novel and improved device that it will always maintain the required resiliency and tension and exert an extremely 30 tight grip and effective frictional engagement with the track rail under any and all conditions of service, and the greater the twisting strain to which the anchor may be subjected the more intense gripping and clamping action is imparted thereto.

The foregoing and such other objects as may appear from the ensuing description are accomplished by the construction, formation, 40 location and combination of the several parts hereinafter more fully described, illustrated by the accompanying drawings, and particularly pointed out in the claims appended hereto, it being understood that slight changes in the precise form, proportions and minor details of the construction may be resorted to without departing from the spirit or sacrificing any of the advantages of the invention.

In the accompanying drawings forming a 50 part of this specification it will be seen that:

Figure 1 is a side elevation of the improved device embodying our invention, showing one end portion broken away, showing a track rail in cross-section and the device attached to the base of said rail showing the position assumed by one of its clamping members before it is caused to clamp the adjacent edge of the rail. 55

Figure 2 is a longitudinal section, in part, of the anchor device, showing it clamped in operative position to the base of a track rail and showing the track rail in cross-section. 60

Figure 3 is a perspective of the device detached from the track rail.

Figure 4 is a plan showing the blank from 65 which the anchor device is formed, and

Figure 5 is a cross-section thereof taken in the plane of the dotted lines 5—5, Fig. 4, looking in the direction of the arrow.

In the embodiment of our invention as 70 illustrated it will be seen that the numeral 1 indicates a railway track rail, and 2 an underlying cross-tie forming a stationary part of the railway road bed and supporting the rail 1, the said rail having a tendency to 75 creep, when subjected to the intense strain caused by the travel of the rolling stock thereover.

This improved and novel anchor is formed from any suitable or desirable metal, but is 80 preferably formed from a single piece or bar of high grade spring steel that is rolled with a reinforced portion 3 at each side of the bar where it is about five-eighths of an inch thick, while its central portion from 4 to 4' 85 is reduced to a thickness of about three-eighths of an inch, the said bar being then cut into the desired or required length for forming the anchor such as is shown in Fig. 4, for forming this particular type of anchor, 90 shown in Fig. 3.

While our special type of rail anchor may be formed in any suitable or desirable manner, the bar 5 is preferably heated to a suitable degree, and by means of a suitable 95 punching device the thinner central portion of the bar from 4 to 4' is sheared as slit rearwardly therethrough to the point 6, thus forming a resilient tongue member 7 between the reinforced side portions 3, then the end 100

portion of the tongue member is so compressed as to form an upward extension thereby forming an integral lip member 8, after which the heated blank is placed in suitable dies for forming the depending body portion 9 by drop forging or stamping, while the last step in its complete formation consists in simply bending over the portion 10 into the formation shown to form the upper overlapping portion of the jaw member 11.

It will be readily perceived that when the anchor device is completely formed it consists of a jaw member 11 provided with an upper portion 10 adapted to tightly clamp 15 against the upper inclined face of the rail base at one side thereof, and a lower member 10' adapted to firmly contact with the lower face of the rail base, a depending body portion 9 having widened reinforced smooth 20 sides, one side of which is adapted to rest in contact with a cross-tie, upwardly and outwardly curved reinforced portions 12, and between said reinforced portions is formed the resilient tongue member 7, provided at 25 its outer end with the extended lip member 8 adapted to firmly grip into contact with the other edge of the rail base when the anchor is forced into its operative position.

It will be obvious that the wide reinforced 30 smooth side portions 3 of the anchor furnish unusual strength thereto and prevent breaking while being forced on the rail and at the same time present a smooth widened bearing surface against the cross-tie all along 35 its face where it is in contact with the tie, thus preventing the tie from being cut, damaged or defaced by the excessive pressure of the anchor against the tie during the passage of the rolling stock thereover.

The anchor device is first adjusted on the rail base by hand, with the lip member and tongue member under upward tension in contact with the lower face of the rail base, it is then forced on the rail by striking the outer 45 face of the jaw member 11 with a suitable sledge or hammer until it is caused to assume the position shown in Fig. 1 with the lip and tongue members under strong upward spring tension, then by a sharp blow of sufficient strength with the sledge or maul at the point 13 the lip member 8 is made to pass the edge of the rail and snap upwardly into close 50 and rigid contact therewith and will remain in its secured position until removed by 55 force.

It will be readily evident that the rail anchor device formed in the manner hereinbefore described possesses unusual strength 60 and efficiency; that it will prevent cutting and damage to the cross-tie; that it is easily and economically produced, and may be readily applied to and disengaged from the base of the track rail.

Having thus described our invention what

we claim and desire to secure by Letters Patent is:

1. A single piece rail anchor formed with a thickened reinforced portion at each side, an intermediate thinner portion forming a resilient tongue member, and a clamping jaw formed at each end portion thereof.

2. A rail anchor formed from a single bar of high grade steel having a thickened reinforced portion at each side thereof throughout its length, and a thinner intermediate slit portion forming a resilient tongue member, and a clamping jaw formed at each end portion thereof.

3. A rail anchor for a track rail formed from a single piece of metal having an overlapping jaw member at one end thereof, a thickened reinforced portion at each side, a depending body portion, an intermediate resilient tongue member formed at the other end portion, said tongue member having an upward extension formed at its outer end forming a clamping member.

4. A rail anchor of the character described, comprising a single piece of metal formed with a thickened reinforced portion at each side throughout its length, a depending body portion, an intermediate resilient tongue member, and a clamping member formed at each end portion thereof.

5. A rail anchor for track rails of the character described, comprising a single bar of metal formed with a thickened reinforced portion at each side throughout its length, and an intermediate slit portion forming a resilient tongue member provided with a clamping member at its outer end.

6. A rail anchor for track rails, comprising a single bar of metal formed with an overlapping clamping member at one end portion, a thickened reinforced portion formed along the sides thereof, a thinner intermediate portion forming a resilient tongue member at the other end portion, a depending body portion and an upward extension forming a clamping member at the outer end of said tongue member.

7. A rail anchor for track rails, comprising a single piece of high grade spring steel formed with a thickened reinforced portion at each side throughout its length, an overlapping jaw member formed at one end, a depending body portion intermediate its ends, and a thinner slit portion intermediate its sides forming a resilient tongue member having a clamping member formed at its outer end disposed between the reinforced sides.
